UNITED STATES PATENT OFFICE.

JOHN R. WORRINGTON, OF PENFIELD, NEW YORK.

ROLL HOLDER.

Application filed May 13, 1927. Serial No. 191,062.

The object of this invention is to provide an improved form of supporting bracket for toilet paper rolls.

This and other objects of this invention will be fully illustrated in the drawing, described in the specification and pointed out in the claims at the end thereof.

In the accompanying drawing:

Figure 1 is a perspective view of the supporting bracket as it appears when attached to the wall with a paper roll supported thereon.

Figure 2 is a partial plan and sectional view of the supporting bracket as it will appear when mounted on the under side of a shelf.

Figure 3 is a perspective view of the supporting bracket mounted on a backing plate that in turn may be suspended from a wall.

In the several figures of the drawing, like reference numerals indicate like parts.

The supporting bracket forming the subject matter of this invention makes it possible to mount a paper roll much quicker and easier than is possible with supporting brackets now used for this purpose. As illustrated in the figures the supporting bracket comprises the bracket member 1 which carries at the outer end the pivot or rod member 2. The bracket member may be formed of wood or other suitable material and is provided with an anchoring means such as the screw 3 by means of which the anchoring member may be fastened to the wall. The outer end of the anchoring member is enlarged in the form of a ball 4 and in this enlarged end is anchored the pivot or rod member 2. This member comprises a rod of suitable material which carries on the free end another ball shaped enlargement 5. The rod or pivot member 2 has the length of a roll of toilet paper so that when such a roll is slipped over the rod it will form a pivot or fixed axis therefor on which the paper roll will rotate when paper is unwound from it.

The ball member 5 formed at the free end of the pivot or rod member 2 projects beyond the length of the paper roll to be supported on the supporting bracket and the diameter of this ball member is slightly less than the inside diameter of the hollow center of the paper roll, so that the paper roll can be readily slipped over the ball member and located on the rod member between the ball member 4 at

one end and the ball member 5 at the other end. The inclined or curved surfaces of the ball members serve to center the roll of paper on the rod or pivot bar but also form a shoulder that will keep the paper roll from sliding off the rod or pivot bar as the paper roll is rotated on the unwinding of some of the paper.

As illustrated in Figure 1 the supporting bracket may be mounted on a vertical wall with its pivot member projecting either to the right or left depending on which way will be the position in which the paper roll can be placed on the bracket the easiest.

In Figure 2 I have illustrated the supporting bracket mounted on the under side of a shelf, that is, on a horizontal wall and in this position too the pivot or rod member may be turned to make the mounting of the paper roll as easy as possible.

In the form illustrated in Figure 3, the supporting bracket is shown as mounted on a backing or base plate 6 which in turn has an eye 7 or other suitable means provided thereon by means of which the backing or base plate 6 can be attached to or hung on the wall.

I claim:

1. A fixed self centered supporting bracket for paper rolls comprising a supporting member, anchoring means at one end of said supporting member, an enlarged ball member of uniform diameter at the other end of said supporting member, a fixed shaft member supported in said enlarged ball member and a second enlarged ball member of uniform diameter at the free end of said pivot member.

2. A fixed self centered supporting bracket for paper rolls comprising a supporting member, an enlarged ball member of uniform diameter at the outer end of said supporting member, a fixed shaft member anchored in said enlarged ball member and projecting at right angles to said supporting member, a second enlarged ball member at the outer end of said pivot member, said ball members forming an inclined shoulder at each end of said pivot member adapted to center and hold a paper roll between them in place on said pivot member when slipped over said second ball member.

In testimony whereof I affix my signature.

JOHN R. WORRINGTON.
